ELECTRICAL CONVERTING APPARATUS

Richard U. Clark, Fort Wayne, Ind.

Application October 14, 1938, Serial No. 235,086

8 Claims. (Cl. 250—36)

The present invention relates to electrical converting apparatus and particularly to circuits used in conjunction with electron discharge tubes and their associate equipment when employed for the purpose of converting direct current into alternating current, or pulsating current, or in converting from one voltage of direct current to a higher or lower voltage of the same.

Among the objects of the present invention is to provide an electrical conversion circuit in which the electron discharge tubes to be associated therewith are caused to oscillate at a fairly constant frequency regardless of the amount or nature of the out-put load supplied by the converter; also to provide a conversion circuit adapted to give good regulation of out-put load voltage regardless of the nature or amount of the load; as well as to provide a circuit which incorporates a suitable time delay device for applying the plate voltage to the inverter tubes.

Further comprehended within my invention is a circuit which is nonstalling and self starting in the event of partial stalling; to provide a new means for deriving cathode heating power from the inverter circuit without the need of adding extra parts and an improved automatically controlled method of making and breaking the discharge current through the electron discharge tube or tube sections which is particularly adapted for use in electron discharge tubes such as described and covered in Patents No. 2,130,380 and Reissue No. 20,727 issued to the present inventor.

Many attempts have been made in the past to devise inversion circuits for use with vapor electric tubes for changing direct current to alternating current but all of the circuits heretofore brought forth in the form of parallel inverters have had the common failing that they may stall or fail through over-load or minimum load conditions, and when so stalled, are no longer self-starting.

When such inverters stall a high current arc forms and often ruins the electron tube cathodes and even where expensive circuit breakers are used to prevent high current arcs there is no guaranty that they may not fail to work. Also they do not help in any way to correct the fault or stalling cause.

In the series type of inverter there is generally less danger that stalling will take place than in the parallel type, but here again a sacrifice in efficiency is made as the energy loss due to the required use of two separate cathodes

is considerable. There is also a tendency for commutation to fail at light loads causing the inverter to stall.

In addition to the foregoing no practical circuits of the series type have been heretofore devised for low voltage operation, nor has any simple circuit which embodies fault correction been heretofore known.

Another inefficiency common to many prior types of inverters is that they incorporate grid phase control systems for starting of the arc and condenser assisting means for extinguishing the arc and these circuits are claimed to operate purposely under other than resonance conditions.

In the present circuit, operation is had at its resonant frequency. When correction of faults is taking place and under no load conditions, the natural period of the circuit may however change due to the automatic action of the correcting agency. The timing of the grid plate voltage relation once the inverter is started is obtained in the present invention by the combined action of coupling of the grid transformer to the plate circuit plus periodic rise and fall in voltage of the center point on the in-put side of the circuit which fluctuates in voltage in unison with each pulse through the inverter tubes or tube sections. This point on the in-put which supplies the fluctuating voltage is so devised as to give automatic control of frequency.

Further objects and advantages of the present invention will become apparent upon consideration of the circuit shown in the accompanying drawing.

The drawing, for illustrative purposes and not as limiting my invention, shows diagrammatically one form of circuit for carrying out the present invention, and in longitudinal section an electron discharge tube connected therewith.

Referring to the drawing, for simplicity, the direct current input is shown as a battery connected to switch 15 and 15—a. The alternating or pulsating power output of the device may take several conventional forms; the inductive coil 32 being one conventional form of arranging output connections.

There is shown an electron discharge tube 1 having a common cathode 2, grids 3 and 4 connected to leads or conductors 3^a and 4^a, and plates or anodes 5 and 6 connected to suitable leads or conductors 5^a and 6^a. A center tapped inductance 7 having a center connection at point 8 connects at one end to plate 5 and the other end to plate 6. Connected to point 8 is a special ballast resistance device 9 having elements 55

38 and 31. Element 38 connects to point 8 at one end and to a small inductance 18 at the other end. There is also an inductance 11 used in conjunction with inductance 18 in the plate circuit. These two inductances have a common connection through a thermal relay 12, which in turn connects into the tank condenser 13, the remaining terminal of which is connected to the normally positive end of the cathode, or cathode heater, or heaters through conductor 14. The plate voltage in-put supply, shown as a battery, connects to inductance 11 through switch 15, which switch is also made as a part of, and directly connected to, filament switch 15-a. The plate battery's negative terminal 16 connects through an isolation inductance 18 to the positive cathode terminal of the tube and also to the positive of the cathode battery, which may be common with the plate batery, and whose negative terminal in turn connects with the cathode of the tube through conductor 17. The plate tuning condenser 19 and the primary of the grid transformer 20 are connected in series and across the two anode conductors 5^a and 6^a. The outside secondary terminals of the grid transformer 20 are connected to the tube grids through conductors 3^a and 4^a. The center tap 28 of the grid transformer secondary is connected to resistor 21 and one terminal to condenser 22. The remaining terminals of resistor 21 and condenser 22 are connected to the junction of the condenser 24 and the resistor 23. Shunting condenser 13 are resistors (optionally inductive) 25 and 26. Condenser 27 is connected in parallel with resistor 26. Resistor 23 connects to the common junction of 25, 26 and 27. Said junction is joined also to one terminal of the ballast resistor 31. Resistor 31 is connected to condenser 24 at its remaining terminal. 40 To start the inverter shown in the drawing, operating switch 15-15-a is closed. This supplies electric energy to cathode 2 and supplies plate voltage to the tube anodes through (normally closed) thermal switch 12. Condenser 45 13, which is of high capacity, say 200 microfarads, immediately starts to charge, drawing a momentary high current surge from the plate battery. This charging surge heats the thermal element of relay 12, temporarily opening the 50 plate circuit which is common to both tube anodes. By the time the thermal relay 12 cools sufficiently to close, the tube cathode is heated and emission started. Simultaneously periodic electrical oscillation is started by virtue of the 55 tuned coupling of transformer 20 between the plate and grid circuits of the tube. For the short initial period during which relay 12 is closed, no appreciable plate current flows since the cathode is cold. In the event the inverter 60 tube cathode is hot from previous use when turned on, plate current of short duration may flow, but not sufficiently long to damage the cathode before relay 12 opens. Subsequently upon the automatic re-closing of relay 12, the 65 device will start in the normal manner. When the thermal switch 12 closes the second time in starting, the potential of both grids is 70 boosted by the action of choke 11, condenser 13, transformer 20 and the inter-connected resistance network, and because of slight differences in grid control ratios, naturally inherent in the tube structure, one circuit through the tube will ionize and fire before the other and from this point on both sections of the tube will 75 ionize and continue to oscillate as a conventional

coupled oscillator, except that the grid potential for initiating ionization, as desired, is timed by the voltage surges across 25 and 27, which surges originate across the direct current in-put choke and are transmitted to condenser 13 and its associate network. 5

Undulating voltage waves are generated as follows: with circuit excited by D. C., current flows to the tube plates with alternating conduction through the two sections, (plate to cathode 10 section), of tube, causing a cyclic rise and fall of current through series inductances in the in-put circuit, due to the inductances being partially saturated because of the short circuiting effect of the gas tube when conducting current. 15 This rise and fall of current produces voltage undulations across inductors 10 and 11 or from their junction to any point on the negative D. C. supply. 15

The reason for voltage across condenser 13 is 20 due to the passage of undulating current through condenser 13. The frequency of this undulating current and voltage tends to vary slightly as the output load of the inverter is changed. 25 When the load is increased the inverter input must supply more current to take care of the demands of the increased load which of course lowers the input inductances due to the tendency to short circuiting effect. As the inverter strives to draw more current which must be 30 passed through the input, the input inductances pass more steady D. C. and with the lowered effective inductance due to approaching saturation, tends to cut down the amplitude of the 35 variable current through the inductances and therefore the amplitude of the voltage across the condenser 13. The resulting tendency from this lowering of impedance is to increase the frequency of oscillation of the inverter but the 40 concurrent rise in resistance due to the additional current passing through the thermal exchange resistor 8 through its coil or filament 30 raises the temperature of 30 and also 31. 31 having the property of decreasing in value when heated, tends to increase the effective capacity 45 of condenser 24 by lowering its effective series resistance, thereby tending to tune the grid transformer secondary to a lower frequency than previously, thus causing a fair degree of stabilization. In other words this prevents the frequency from changing materially, of the system as a whole. 50

The grid circuit tuning condenser 24 operates 55 in conjunction with condenser 22 although condenser 24 is chosen of a value such as to tune the grid transformer, both halves of which it shunts, and condenser 22 affords chiefly a bypass action. Condenser 24 tunes because of variations in resistor 31 in series with it. 60

Inasmuch as the grid control timing of the tube is related to resistors 25 and 26, it is obvious that a particular variation in grid timing may be obtained by utilizing resistors having a specific coefficient of resistance wherein the resistance 65 value will vary in proportion to the temperature rise of the resistor, or a resistance winding having an inductive value may also be used. Either one, or both, may be chosen to establish a particular predetermined variation in grid timing. 70

Improved regulation of the device is accomplished by taking advantage of the ripple voltage across condenser 13, since this ripple voltage decreases in magnitude as the output load increases. For example, if resistor 25 is provided 75

having a high negative coefficient of resistance, its instantaneous resistance value can be made to increase in proportion to the instantaneous drop in the ripple voltage across the condenser 13, thus causing the fluctuating voltage, which is applied to the grids of the tube, to change phase providing frequency stabilization and longer conduction between the anode and cathode, which will supply the increased power drawn in the output circuit as the occasion demands. Regulation is partly from A. C. fed through 13 to indirect cathode heater. For directly heated cathodes this A. C. may be rectified.

Another important feature of this invention is the method employed for utilizing electrical energy from the input circuit to assist in energizing the cathode heating element or elements of the tube, thus preventing, under light or no load conditions, stalling or the inoperative condition which results in conventional circuits. The A. C. component through condenser 13 prevents this.

Stalling is overcome in the present circuit through the use of energy available in the condenser 13. This condenser, in addition to its effect upon the thermal relay and the grid timing circuit, also supplies energy to the cathode, in inverse proportion to the load through the positive leg of the cathode of the heater in the tube. The largest amount of energy exists across the condenser 13 when the output load is small, and vice versa. Hence, by utilizing a properly proportioned cathode heating element with this circuit, sufficient cathode energy is supplied by condenser 13 during light load operation to prevent excessive discharge of the cathode battery. Likewise when the circuit is operating under heavy load conditions, the heating effect of the plate current may be made to equal or exceed the cathode cooling effect. Therefore, regardless of the load, the cathode battery is not excessively drained. By virtue of the foregoing, the only excess energy drawn from the cathode section of the battery is drawn during the short period required for starting, and due to the limited amount of energy thus consumed, no separate battery or "battery charging" connections are required as is the case in conventional inverters.

As a further improvement in controlling the frequency of the alternating current output of my inverter, I provide a bulb 8 in which ballast filament 38 and resistor 31 are thermally associated. Since filament 38 is in series with the plate circuit of the tube, it will follow that the filament will emit and transfer heat to the resistor 31 in proportion to the plate load.

Material with a negative coefficient of resistance is chosen for resistor 31 and since this resistor is in the grid circuit of the tube it will follow if the output load in the plate circuit increases, the filament 38 will radiate more heat to resistor 31, causing a reduction in grid loss and providing greater output capabilities in the plate and output circuit.

Material having a high positive coefficient of resistance is selected for the ballast filament 38 so as to prevent oscillation failure through a power output overload. Since the filament 38 is in series with the plate battery, a sudden overload will result in a rapid temperature rise in the filament, hence, an increase in resistance to a point where oscillation will automatically start. Under normal operating conditions, equilibrium between the grid and plate circuits is thus quickly established and maintained.

It is evident from the foregoing that the tube

and the associated inverter circuit will continue operation under both extremely light and excessively heavy loads. However, when either of these two conditions exists beyond normal operating ranges, there will be power fluctuations in the output circuit and corresponding fluctuations in the ionization paths of the tube. Hence, the device will give visual indication of improper operating conditions.

I also wish to point out that it is possible to vary the constants of the circuit described to automatically correct overload conditions to a high predetermined level without wide power fluctuations in the output.

Having thus described my invention I claim: 15

1. In combination in an electronic converter, a tube having plates and grids, inductances connecting the plates, plate in-put means combining two plate connecting inductances to an electrical in-put supply, a thermal relay interconnecting said two inductors, a tube cathode, a condenser, means for initially charging the condenser through the relay and disconnecting the plate source from the plates and automatically reconnecting the same when the tube cathode is heated to emitting temperature, a grid tuning network, and a thermal exchange resistance control device in series with the plate supply and the operation thereof in series with the grid tuning network. 30

2. In combination in an electronic converter, a tube having plates and grids, an inductance connecting the plates thereof, grid to plate coupling means, plate in-put means, inductances connecting the plates to an electrical in-put supply, a thermal relay interconnecting the inductances, a condenser, a cathode, a condenser to cathode connection to said relay, means for charging the condenser through the relay and temporarily disconnecting the plates from the plate in-put, said last named means automatically reconnecting the plates and plate input when the cathode is heated to emitting temperature, a grid tuning network across the input supply and connecting same with the condenser, a grid tuning condenser, and a thermal exchange resistance control device in series with the plate in-put, the operation of the thermal exchange resistance control device being in series with the grid tuning condenser. 50

3. In combination in an electronic converter, a dual vapor electric tube, a tuned inductance connecting the plates thereof, grid to plate coupling means, plate in-put means combining two inductances connecting said plates to an electrical in-put supply, a thermal relay interconnecting said two inductances, a condenser, a cathode, a condenser to cathode connection to said relay, means for initially charging said condenser through the relay thereby temporarily disconnecting the plate in-put means from the plates, and automatically reconnecting same when the cathode is heated to emitting temperature, a grid tuning network, and a thermal exchange resistance control in series with the plate in-put supply, so as to provide a converter circuit stable in operation at a desired frequency, which will feed energy from the plate in-put to the cathode circuit during operation, and prevent stalling due to incorrect loading. 70

4. A parallel electronic converter comprising a dual vapor electric tube, a tuned inductance connecting the plates thereof, grid to plate coupling means, plate in-put means combining two inductances connecting said plates to an elec- 75

- trical in-put supply, a thermal relay interconnecting said two inductors, a condenser to cathode connection to said relay, means for initially charging said condenser through said relay there-
5 by temporarily disconnecting said plate source from said plates, and automatically reconnecting same when said tube cathode is heated to emitting temperature, combined with a grid tuning network across said in-put supply to cathode
10 condenser, and a thermal exchange resistance control device, in series with said plate supply and the operation thereof in series with a grid tuning condenser, suitable starting switches as-
15 sociated with said circuit, the foregoing means associating to provide a converter circuit which will operate stably at a desired frequency, which will feed energy from the plate in-put to the cathode circuit during operation and which will prevent failure or stalling due to incorrect load-
20 ing of the out-put system.
5. In combination in an electronic converter, a tube having plates and grids, inductances connecting the plates, plate in-put means combin-
25 ing two plate connecting inductances to an elec-
trical in-put supply, a thermal relay intercon-
necting said two inductors, a tube cathode, a
condenser, and means for initially charging the
condenser through the relay and disconnecting
30 the plate source from the plates and automatic-
ally reconnecting the same when the tube cath-
ode is heated to emitting temperature.
6. In an electrical converter, an electronic tube including a plurality of plates, a plurality of grids and a cathode having two terminals, a con-
35 nection including a source of potential between said plates and said cathode, means coupling said plates and grids for causing current to flow from said cathode to each of said plates respec-

tively, a plurality of inductances in series in said connection whereby input fluctuation will appear between said inductances, a condenser connected between a point between said inductances and one terminal of said cathode, and means for connect-
5 ing the other terminal of said cathode to said source whereby said input fluctuations will initially excite said cathode and continuously main-
tain it at an effective emitting temperature.

7. In an electrical converter, an electronic tube 10 including an anode, cathode and grid, a connec-
tion including a source of potential between said anode and cathode, means coupling said anode and cathode for causing current variations through the tube at a desired operating fre-
15 quency, said means including a grid tuning con-
denser and a resistance which becomes less as its temperature is raised in series therewith, and means for stabilizing the generating frequency comprising a heating means connected in series 20 in said connection, said last named resistance being exposed to heating by said heating means.

8. In an electrical converter, an electronic tube including an anode, cathode and grid electrode, means for coupling said anode and grid for caus-
25 ing variations in current in said tube at a de-
sired operating frequency, a connection between said anode and cathode including a source of potential, and a plurality of inductances, an in-
put condenser connected between said cathode 30 and a point between said inductances, and means for utilizing the ripple voltage across the input condenser due to its said connections for timing the said current comprising an impedance across said input condenser and means for coupling 35 said impedance to said grid.

RICHARD U. CLARK.
